UNITED STATES PATENT OFFICE.

GUSTAVE M. FAUSER, OF NEW YORK, N. Y., ASSIGNOR TO TINGUE MANUFACTURING COMPANY, OF NEW YORK, N. Y., A CORPORATION OF CONNECTICUT.

DESIGN FOR A WOVEN FABRIC.

Application filed September 29, 1922. Serial No. 3,846. Term of patent 7 years.

To all whom it may concern:

Be it known that I, GUSTAVE M. FAUSER, a citizen of the United States of America, residing at New York city, county and State of New York, have invented a new, original, and ornamental Design for Woven Fabrics, of which the following is a specification, reference being had to the accom-

panying drawing, forming a part thereof, and wherein the figure is a plan view of a woven fabric showing my new design.

I claim:

The ornamental design for a woven fabric, as shown.

GUSTAVE M. FAUSER.
